WILLIAM H. CLARKE, OF NEW YORK, N. Y.

AUTOMATIC AIR-BRAKE.

SPECIFICATION forming part of Letters Patent No. 635,995, dated October 31, 1899.

Application filed May 9, 1898. Serial No. 680,085. (No model.)

To all whom it may concern:

Be it known that I, WILLIAM H. CLARKE, a citizen of the United States, residing at the city of New York, in the borough of Brooklyn and State of New York, have invented certain new and useful Improvements in Automatic Air-Brakes, of which the following is a full, clear, and exact description.

This invention relates to automatic fluid-pressure train-brakes. Its object is to furnish means by which a high braking force may be utilized when desired without injurious effects—such, for instance, as the locking or sliding of wheels, which frequently takes place at moderate speeds when excessive pressure is applied to the brake-shoes.

Experiment in the art has demonstrated that when a train is at full speed a higher pressure may be safely applied to the brake-shoes without locking and sliding the wheels than when the momentum of the train has been nearly checked. It is therefore evident that the maximum efficiency of the brakes will be obtained if an excessive pressure is used at high speed and gradually reduced as the train approaches a full stop.

In automatic air-brake systems, such as the Westinghouse, it is the practice in making an emergency application of brakes to vent both the auxiliary reservoir and the train-pipe into the brake-cylinder in order that an extra pressure may be obtained. This venting of the train-pipe into the cylinders not only hastens the stop by furnishing extra pressure, but incidentally accelerates the response of the triple valves throughout the train.

In the practice of my invention I utilize the standard (Westinghouse) capacity relation between the auxiliary reservoir and the brake-cylinder and limit the pressure which shall enter the brake-cylinder in either service or emergency application of brakes to a predetermined amount in each, and then by increasing the leverage of the brake-rigging I am able to secure the desired maximum brake stress in emergencies.

My invention not only serves to automatically limit the service-pressure in the brake-cylinder to, say, forty pounds per square inch, (the altered leverage in the brake-rigging giving the desired results with this pressure,) but it also provides means for automatically

reducing to a predetermined proportion to the pressure remaining in the auxiliary reservoir any pressure which may enter the brake-cylinder in excess of the maximum desired. Further, the use of diaphragms instead of pistons precludes the possibility of leakage, which might render the device inoperative. In these respects my present device constitutes a material improvement on that described and claimed in Letters Patent granted to me December 31, 1895, No. 522,324.

My invention is illustrated in the accompanying drawing, which represents a section of a standard Westinghouse triple valve with my improved valve fitted thereto.

Referring to the drawing by letter, A represents the triple valve of ordinary construction and operation; B, the port leading to the brake-cylinder (not shown) through a suitable pipe b; C, the auxiliary reservoir, and c the port leading from the auxiliary reservoir to the triple valve.

D is the casing of my improved valve, preferably secured between the triple valve and the reservoir or cylinder, to which the triple valve is usually attached. It contains two diaphragms d and d' on a common stem d", carrying two valves, one designated herein as the "intercepting-valve" d², controlling the passage from the auxiliary to the triple, and the other the "discharge-valve" d³, governing the escape-port a', leading to the atmosphere, for brake-cylinder pressure. Both valves are rubber-seated. The area of the diaphragm d' is about one-third larger than that of d; but this proportion may of course be varied as desired. The stem of the intercepting-valve projects loosely through a yoke d⁵ and carries a head d⁶, which engages with the yoke. The discharge-valve d³, which is hollow, carries an end cap d⁹, through which the stem passes, the stem terminating in a head d⁴, with which the cap may engage. The valve contains a spring d⁵, bearing against the head d⁴, through which the valve is seated on the movement of the diaphragms to the left. The head d⁴ and the cap d⁹ are both provided with air-passages, (shown in dotted lines,) and the valve is pierced laterally to connect port a with its interior chamber. The port a, by which air from the brake-cylinder passage passes to the discharge-valve

a' and larger diaphragm *d'*, is restricted, as shown. In the usual service applications of the brakes auxiliary-reservoir pressure is admitted by the triple valve comparatively slowly into the brake-cylinder passage and passes slowly to the larger diaphragm *d'* by reason of the restriction of the port *a*. Should the amount of pressure expanded thus into the brake-cylinder by the triple valve exceed two-thirds of the remaining auxiliary-reservoir pressure upon the smaller diaphragm *d*, it will be seen that the larger diaphragm *d'* will overbalance the other by reason of the relative sizes of the diaphragms and both will be forced to the right, carrying with them both valves, closing communication between the auxiliary reservoir and the triple valve and opening the escape-port *a'* for a comparatively slow release of brake-cylinder pressure. This depletion of cylinder-pressure will continue until the relative pressures in reservoir and cylinder are again established, when a further depletion will cause the slightly-preponderating pressure on the smaller diaphragm *d* to slowly move both diaphragms to the left, seating the discharge-valve *d³*. Further motion to the left will then be arrested by the resistance of the spring *d⁵* and of the intercepting-valve *d²*, as at this point the yoke *d⁶* will come into contact with the head of the intercepting-valve stem and said valve will be held to its seat by reason of the slight excess of pressure on its left side, the area of that side being somewhat larger than that of its right side. These combined resistances to further movement to the left at this time will accordingly serve to check further escape of brake-cylinder pressure, while retaining in the auxiliary reservoir all of its remaining pressure. When, however, the brake-cylinder pressure is finally released through the usual movement of the triple valve, pressure on the large diaphragm *d'* will also be released through the same port *a* by which it entered and auxiliary pressure will force all parts to their normal positions, as shown in the drawing—*i. e.*, discharge-valve closed and port *a* and intercepting-valve open. In an emergency application pressure from the auxiliary reservoir is admitted suddenly and in large volume to the brake-cylinder and attains the maximum degree therein before it has time to actuate the larger diaphragm *d'*, because of the restriction of the passage *a* thereto, as heretofore described. It is thus evident that full emergency-pressure will be obtained in the brake-cylinder and will be immediately thereafter slowly reduced in the manner before described through ports *a* and *a'* and valve *d³* until the stated proportion to remaining auxiliary pressure is reached, when further escape will be checked and pressure held in both cylinder and reservoir until brakes are released in the usual manner. It is evident also that this operation will be the same whenever a full or nearly full expansion of the auxiliary into the brake-cylinder takes place, whether in emergency or

service applications, and the highest braking efficiency will thus be obtained. Further, the increased brake-pressure available by this device without injurious effects requires a less amount of air in making ordinary stops and allows a greater number of applications of brakes without recharge of auxiliaries. It will also be seen that when holding brakes on grades with auxiliary and cylinder pressures nearly or fully equalized, the triple-valve piston being in its full-application position, if, as frequently happens, the brake-cylinder pressure becomes depleted by leakage this valve will in the performance of its regular functions, as described herein, automatically admit additional pressure into the brake-cylinder from the auxiliary reservoir, thus obviating a dangerous reduction of braking-pressure.

I am aware that an increase in the leverage of the brake-rigging means an increased length of stroke for the brake-cylinder piston; but this increase will be slight and of no more consequence than ordinary "slack adjustment" provides for.

My invention contemplates a differential diaphragm actuated by auxiliary-reservoir and brake-cylinder pressures through a normally-restricted passage, first, to control the port leading from the auxiliary reservoir through the triple valve to the cylinder; second, to automatically reduce any excessive pressure which may for any cause enter the brake-cylinder, and, third, to automatically reduce to a predetermined percentage of the remaining auxiliary-reservoir pressure any pressure in excess of such percentage which may be vented from said reservoir to said cylinder in any application of the brakes.

It is evident that two diaphragms of any desired areas may be employed in my improved apparatus without departing from the spirit of my invention, and I do not limit myself in this respect nor as to any special standard of either emergency or service brake-pressures. In standard systems, such as the Westinghouse, auxiliary-reservoir pressure is at all times practically free to pass to the triple-valve casing, which latter on account of its construction and parts presents many opportunities for leakage. It will be seen that my improved valve retains auxiliary pressure therein at times when such leakages become most dangerous—as, for instance, when brakes are being held with considerable force on grades. Further, as by the action of my improved valve the pressure in the triple-valve casing above its piston being at such times somewhat less than auxiliary-reservoir pressure, it is evident that when the train-pipe pressure is increased in order to release brakes the triple-valve piston will be more quickly and readily moved to the release position than if it was then exposed to auxiliary-reservoir pressure above its piston. These also constitute important features of my invention.

The two diaphragms of different areas on a common stem may be properly designated as a "differential" diaphragm or piston.

Having thus described my invention, I claim—

- 5 1. In an air-brake system the combination of a brake-cylinder and auxiliary reservoir, a triple valve, a port between the reservoir and triple valve and an intercepting-valve controlling said port, an escape-port for brake-cylinder pressure and a discharge-valve controlling the same, said intercepting-valve and discharge-valve being on the same stem and means whereby the pressure in the brake-cylinder will serve to close the intercepting-valve and open the discharge-valve, substantially as described.
- 10 2. In an air-brake system the combination of a brake-cylinder and auxiliary reservoir, a triple valve, a port between the reservoir and triple valve and an intercepting-valve controlling said port, an escape-port for brake-cylinder pressure and a discharge-valve controlling the same, and means whereby the pressure in the brake-cylinder will serve to close the intercepting-valve and open the discharge-valve, and the auxiliary-reservoir pressure thereafter close the discharge-valve, substantially as described.
- 15 3. In an air-brake system the combination of a brake-cylinder and auxiliary reservoir, a triple valve, a port between the reservoir and triple valve and an intercepting-valve controlling said port, an escape-port for brake-cylinder pressure and a discharge-valve controlling the same and means whereby the pressure in the brake-cylinder will serve to close the intercepting-valve and open the discharge-valve, and the auxiliary-reservoir pressure thereafter close the discharge-valve, substantially as described.
- 20 4. In an air-brake system, the combination of a brake-cylinder and auxiliary reservoir, a

triple valve, a port between the reservoir and triple valve and an intercepting-valve controlling said port, an escape-port for brake-cylinder pressure and a discharge-valve controlling the same, and two diaphragms or pistons of different areas acting together to control the intercepting and discharge valves, said diaphragms or pistons being respectively subjected to pressures from the auxiliary reservoir and the brake-cylinder, substantially as described.

5. In an air-brake system, the combination of an auxiliary reservoir, a triple valve, a brake-cylinder, a port connecting same, an escape-port for the brake-cylinder pressure, valves controlling said ports and a differential diaphragm actuating said valves, said diaphragm being subjected on one side to auxiliary-reservoir pressure and on the other side to brake-cylinder pressure, substantially as described.

6. In an air-brake system, the combination of an auxiliary reservoir and triple valve, a port connecting the same, a valve controlling said port and a differential diaphragm actuating said valve, said diaphragm being subjected to auxiliary-reservoir pressure on one side and to brake-cylinder pressure on the other side.

7. In an air-brake system, the combination of an auxiliary reservoir, a brake-cylinder, a passage connecting the same, and a valve device exposed to auxiliary-reservoir and brake-cylinder pressures and adapted to automatically produce and maintain a predetermined ratio between said pressures, substantially as described.

In witness whereof I subscribe my signature in presence of two witnesses.

WILLIAM H. CLARKE.
